COOL SHADE AWNING

Albert C. Ferguson, Jacksonville, Fla.

Application April 3, 1942, Serial No. 437,567

1 Claim. (Cl. 160—223)

This invention relates to a novel and improved all-metal ventilated awning such as is adapted for use on private residences, commercial buildings and the like.

One object of the invention is to structurally and otherwise improve upon similarly constructed awnings and to accomplish this through the medium of a selection and arrangement of parts and, in so doing, to thus meet current demands for substantially indestructible awnings and to likewise fulfill expected requirements of both manufacturers and users.

In carrying out the principles of the invention, I have evolved and produced an appropriately constructed all-metal ventilated awning which is such as to properly promote unhampered circulation of air, one which satisfactorily intercepts outside light rays, functions to shed rain and snow and at the same time performs the desired interior room shading and cooling requirements.

Another object of the invention is to provide a metal ventilated awning which is adjustable, which is readily applicable and removable for repairs and painting and is sufficiently ventilated to minimize trapping of hot air beneath and within its confines, and which will serve efficiently from year to year.

Other objects, features and advantages will become more readily apparent from the following description and the accompanying illustrative drawing.

In the drawing, wherein like numerals are employed to designate like parts throughout the views:

Figure 1 is a perspective view of a metal ventilated awning constructed in accordance with the principles of the instant invention observing same from the inner or under side thereof.

Figure 2 is likewise a perspective view looking at the awning from the outside.

Figure 3 is an enlarged fragmentary sectional view taken on the vertical line 3—3 of Figure 1.

Figure 4 is a fragmentary horizontal section on the line 4—4 of Figure 3, looking in the direction of the arrows.

Figure 5 is a fragmentary detail sectional and elevational view detailing the parts, the view being taken approximately on the plane of the line 5—5 of Figure 2, looking in the direction of the arrows.

Referring now to the drawing by distinguishing reference numerals, it will be seen that the awning as a unit is ready to install and attachable and detachable, and, as before indicated,

is preconstructed of rigid sheet material. It is of triple section construction and substantially visor-shaped in overall appearance. The central section is denoted by the numeral 6 and the triangular vertically disposed end sections are denoted and distinguished by the numerals 7 and 8, these being of duplicate construction. As stated, the end members 8 are triangular in construction and each comprises a vertical marginal frame member 9 which, as shown in Figure 3, is channel-shaped in cross section, this having associated therewith an outwardly and downwardly inclined so-called topping and cornice rail 10, the latter being fastened at its upper end to the corresponding upper end of the frame member 9, as indicated at 11. The topping rail is also channel-shaped in cross section, as brought out to advantage in Figure 5. The end section is completed by the incorporation therein of a plurality of complementary properly spaced horizontal slats. Each slat is substantially zig-zag in cross sectional form. Thus, each slat comprises a flat body or web portion (see Fig. 3) 12 with laterally and oppositely directed and relatively narrow longitudinal edge-flanges 13 and 14, respectively. The slats are arranged between the marginal edge flanges of the frame member 9 and are suitably secured in place with the respective flanges 13 and 14 engaging the flanges of the frame member. Also, these slats are closely spaced in parallelism in order to form an open-work grille to provide for free circulation of air as well as proper shedding of rain and interception of sun rays.

The central section is made up of extensible and retractable louvers whose sections are telescopically connected together, the sections being differentiated by the numerals 15 and 16, respectively. The outer ends of these sections are provided with lateral flanges 17 (see Fig. 5) which are riveted to the web portions of the topping rails or frame members 10. It will be noted that the respective louvers are disposed in parallelism and also disposed angularly to the rails at acute angles to the wall of the building (not shown).

It follows, therefore, that the frame members 9 provide for attachment to the building, the louvers 15 and 16 serve to permit the awning as a unit to be adjusted in length to accommodate varying requirements.

Novelty is thought to reside in the individual horizontal slats which are rigidly anchored at their opposite ends and supported, replaceably, between the coacting inner and outer frame members, these slats being of a cross sectional

shape which provides the oppositely deflected longitudinal edging flanges, the flanges contacting and being rigidly mounted between the side flanges of the channel-shaped inner frame members 9 and being anchored in the outer inclining topping rails or frame members 10.

A careful consideration of the foregoing description in conjunction with the invention as illustrated in the drawing will enable the reader to obtain a clear understanding and impression of the alleged features of merit and novelty sufficient to clarify the construction of the invention as hereinafter claimed.

Minor changes in shape, size, materials and rearrangement of parts may be resorted to in actual practice so long as no departure is made from the invention as claimed.

I claim:

A ready-to-install attachable and detachable preconstructed rigid sheet material ventilating-type window awning of the class described comprising a triple section substantially visor-shaped structure embodying a pair of composite, substantially triangular vertically disposed end sections and an intervening complementary outwardly and downwardly inclined central section, each end section comprising a pair of marginal frame members, there being an inner member of rela-

tively narrow channel-shaped cross sectional form vertically disposed and an outer member also channel-shaped in cross sectional form and constituting a topping and cornice rail inclining 5 outwardly and downwardly, the adjacent upper and coacting ends of the respective frame members being joined together in converging relation, and each end section also including a plurality of individual horizontally disposed slats, said 10 slats rigidly anchored at opposite ends and supported between the inner and outer frame members, the respective slats being zig-zag in cross-section to provide oppositely deflected longitudinal edge-flanges, the flat body portions of said 15 slats being disposed in vertical alignment with one another and the adjacent flanges of the respective slats closely spaced in parallelism in order to form an openwork grille to provide for free circulation of air, proper shedding of rain and interception of sun rays, and said central section embodying extensible and retractible louvers having their outer ends rigidly fastened to said topping rails and being spaced from each other in parallelism and disposed angularly to said rails at acute angles to the wall of the 20 building.

A. C. FERGUSON.
